Louin BERRY

BY

A. L. Jackson

ATTORNEY

UNITED STATES PATENT OFFICE

LOUIN BERRY, OF FORT WORTH, TEXAS

MATCH BOX

Application filed April 1, 1930. Serial No. 440,658.

My invention relates to boxes and more particularly to match boxes; and the object is to provide match boxes with securing means which are concealed from inspection and which will hold the matches securely sealed until the box is opened and the principal object and advantage is that the box cannot be opened by small children. Other objects and advantages will be fully explained in the following description and the invention will be more particularly pointed in the claims.

Reference is had to the accompanying drawings which form a part of this application.

15 Fig. 1 is a horizontal section of the container, showing the location of the carrier and the match box therein and the operating mechanism.

Fig. 2 is a side elevation of the container.

20 Fig. 3 is an end elevation of the carrier.

Similar characters of reference are used to indicate the same parts throughout the several views.

A container 13 has a compartment 1 for 25 containing a match box 3 and a compartment 2 for concealing the locking means. A carrier 4 for the match box 3 is movable in and out of the container 13 and is provided with a handle 14. Means are provided for locking the carrier 4 within the container 13. An eye 5 is attached to the inner end of the carrier 4 and a spring latch 6 is provided for locking and holding the carrier within the container 13. The latch 6 has a shank 7 which 30 operates through a guide 8 which is rigidly attached to the support 15 which is attached rigidly to the container 13. The latch 6 is provided with a knob 10 for depressing the latch 6 for releasing the same from the eye 40 5 and carrier 4. An opening 11 is made in the side of the container 13 for inserting a finger for depressing the knob 10. A curved tubular passage 12 is provided for inserting and extending a finger to the knob 10. One 45 of the advantages of the match box is that a person's finger will have to be long enough to reach in and depress the knob 10 in order that the eye 5 may be released from the carrier 4. A child's finger would not be long 50 enough for this purpose and so a child could

not open the match box. The tubular passage 12 is also curved so that a stick or other device cannot be used to depress the knob 10.

The invention has been shown in connection with a match box. It is apparent that 55 the invention can be used for various other receptacles, such as pantries, medicine chests, series of drawers, and any inclosure in which articles are placed for safe keeping.

It is apparent that various changes in the 60 sizes, proportions, construction and arrangement of the several parts may be made without departing from my invention.

What I claim is,—

1. A match box comprising a receptacle and 65 a carrier removably mounted therein, a match container mounted in said container mounted in said carrier, an eye attached to the end of said carrier, a manually operable spring latch secured to the interior of said receptacle 70 and concealed therein, said receptacle having an opening in the side thereof, and a tubular curved passage rigid with said receptacle leading from said opening, and terminating in close proximity to said spring latch. 75

2. A match box comprising a receptacle having a storing compartment and a working compartment, a carrier removably mounted in said receptacle, a match container mounted in said carrier, securing means attached to 80 the end of said carrier, a manually operable spring latch secured to the interior of said receptacle and provided with a depressible knob, said receptacle having an opening in the side thereof, and a curved tubular passage 85 rigid with said receptacle and leading from said opening and terminating in close proximity to said knob.

In testimony whereof, I set my hand, this 90 20th day of March, 1930.

LOUIN BERRY.
